(57) **CLAIM**

The ornamental design for a pair of earphones, as shown and described.

DESCRIPTION

FIG. 1 is a perspective view of a pair of earphones showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting portions of the pair of earphones in FIGS. 1, 3, and 6 show features that form no part of the claimed design. The difference in shading indicates a contrast of appearance and does not depict any particular color, texture, or material.
